US00D723621S

(12) **United States Design Patent**
Heinrichs

(10) **Patent No.:** **US D723,621 S**
(45) **Date of Patent:** **** Mar. 3, 2015**

(54) **ELASTOMERIC LOOP ASSEMBLY**
(71) Applicant: **Bedford Industries, Inc.**, Worthington, MN (US)
(72) Inventor: **Curtis John Heinrichs**, Sibley, IA (US)
(73) Assignee: **Bedford Industries, Inc.**, Worthington, MN (US)
(**) Term: **14 Years**
(21) Appl. No.: **29/436,895**
(22) Filed: **Nov. 9, 2012**
(51) LOC (10) Cl. **19-08**
(52) U.S. Cl. **D20/22; D20/28; D20/43**
(58) **Field of Classification Search**
CPC G09F 3/00; G09F 3/02; G09F 3/04; G09F 3/06; G09F 3/08; G09F 3/14; G09F 3/16; G09F 3/20; G09F 3/202; G09F 3/205; G09F 2003/00; G09F 2003/0254; G09F 2003/0264; G09F 2003/0266; A45C 11/18; B42F 11/00; B42F 15/00; B42F 15/0041; B42F 15/0023; B65D 23/14; B65D 33/06

Primary Examiner — Mary Ann Calabrese

(74) Attorney, Agent, or Firm — James L. Young; Westman, Champkin & Koehler, P.A.

(57) **CLAIM**

The ornamental design for an elastomeric loop assembly, as shown and described.

DESCRIPTION

FIG. 1 is a front view of a first embodiment thereof;
FIG. 2 is a back view thereof;
FIG. 3 is a side view thereof, as taken from the left side of FIG. 1;
FIG. 4 is a side view thereof, as taken from the right side of FIG. 1;
FIG. 5 is a top view thereof;
FIG. 6 is a bottom view thereof;
FIG. 7 is a front view of a second embodiment thereof;
FIG. 8 is a back view thereof;
FIG. 9 is a side view thereof, as taken from the left side of FIG. 7;
FIG. 10 is a side view thereof, as taken from the right side of FIG. 7;
FIG. 11 is a top view thereof;
FIG. 12 is a bottom view thereof;
FIG. 13 is a front view of a third embodiment thereof;
FIG. 14 is a back view thereof;
FIG. 15 is a side view thereof; as taken from the left side of FIG. 13;
FIG. 16 is a side view thereof; as taken from the right side of FIG. 13;
FIG. 17 is a top view thereof; and,
FIG. 18 is a bottom view thereof.
